UNITED STATES PATENT OFFICE

101,644

DESIGN FOR A BASE FOR A BEVERAGE DISPENSING DEVICE

James W. Lehman, Baltimore, Md., assignor to
The Coca-Cola Company, Atlanta, Ga., a corporation of Delaware

Application July 17, 1936, Serial No. 63,907

Term of patent 14 years

To all whom it may concern:

Be it known that I, James W. Lehman, residing at Baltimore, State of Maryland, have invented a new, original, and ornamental Design for a Base for a Beverage Dispensing Device, of which the following is a specification, reference being had to the accompanying drawing, forming part thereof.

Figure 1 is a perspective view of a base for a beverage dispensing device showing my new design;

I claim:

The ornamental design for a base for a beverage dispensing device, as shown.

JAMES W. LEHMAN.
